US0D1106268S

(12) **United States Design Patent** (10) **Patent No.:** **US D1,106,268 S**
(45) **Date of Patent:** **** Dec. 16, 2025**

(54) **PAINT PUMP HOUSING**

(71) Applicant: **Wagner Spray Tech Corporation**,
Plymouth, MN (US)

(72) Inventors: **Douglas P. Pozanc**, Winona, MN (US);
Paul Fally, Hamburg (DE); **Heiko Tullney**, Aumühle (DE)

(73) Assignee: **Wagner Spray Tech Co.**, Plymouth,
MN (US)

(**) Term: **15 Years**

(21) Appl. No.: **29/829,226**

(22) Filed: **Mar. 3, 2022**

(51) **LOC (15) Cl.** **15-02**

(52) **U.S. Cl.**

USPC **D15/7**; D23/225

(58) **Field of Classification Search**

USPC D15/7-9; D23/225, 231, 232; D13/107;

D10/86

CPC F04B 1/005; F04B 33/00; F04B 33/005;
F04B 15/00; F04B 15/02; F04D 13/06;

F04D 25/0673; F04D 25/08

See application file for complete search history.

(57) **CLAIM**

The ornamental design for the paint pump housing as shown and described.

DESCRIPTION

FIG. 1 is a perspective view of the paint pump housing.

FIG. 2 is a front view of the paint pump housing.

FIG. 3 is a rear view of the paint pump housing.

FIG. 4 is a top view of the paint pump housing.

FIG. 5 is a bottom view of the paint pump housing.

FIG. 6 is a right side view of the paint pump housing; and,

FIG. 7 is a left side view of the paint pump housing.

The details shown in broken lines form no part of the claimed design.

1 Claim, 7 Drawing Sheets
